UNITED STATES PATENT OFFICE.

JOHN ROGERS FLANNERY AND ETHAN I. DODDS, OF PITTSBURGH, PENNSYLVANIA,
ASSIGNORS, BY MESNE ASSIGNMENTS, TO FLANNERY BOLT COMPANY, OF PITTS-
BURGH, PENNSYLVANIA, A CORPORATION OF DELAWARE.

STAY-BOLT STRUCTURE.

Application filed September 10, 1919. Serial No. 322,871.

To all whom it may concern:

Be it known that we, JOHN ROGERS FLANNERY and ETHAN I. DODDS, citizens of the United States, and residents of Pittsburgh, 5 in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in staybolt structures for boilers, and the 15 method of making and installing the same,— one object of the invention being to provide a combined bearing member for the bolt head and closure for the opening in the boiler sheet, which can be assembled on the 20 bolt head in the shop and which shall have an initial universally movable or adjustable mounting relatively to the boiler sheet whereby accurate alignment of the staybolt with its points of connection with the 25 respective boiler sheets may be effected, and which shall be firmly united to the boiler sheet after such adjustment shall have been made, by welding.

A further object is to provide a bearing 30 member in the form of a hollow plug to enter the opening in the boiler sheet and welded to the latter, said bearing member or plug permanently enclosing the head of the staybolt and affording a bearing for said 35 head, and having such interior configuration and dimensions as to provide ample clearance for the bolt head.

With these and other objects in view, the 40 invention consists in certain novel features of construction and combinations of parts as hereinafter set forth and pointed out in the claims.

In the accompanying drawings; Figure 1 is a sectional view showing an embodiment 45 of our invention; Figures 2 and 3 are views illustrating the manner of making the combined bearing plug and closure, and Figures 4, 5, 6, 7 and 8 are views illustrating modifications.

50 1 represents the outer sheet of a boiler and 2 the inner boiler sheet.

The outer boiler sheet is made with an opening 3 having a general tapering form and a portion of the wall of said opening

may be rounded transversely of the thickness of the sheet to provide a seat 4 on which a combined bearing plug or member and closure 5 may have an initial universally movable mounting.

The plug or member 5 may be made of a single piece of metal and may have the spherical form shown in Figures 1 and 3, with an opening 5^a for the accommodation of the neck of the staybolt. The blank from which the plug or member 5 is made is provided with a plurality of V-shaped notches or recesses 6 and this blank is forged to the approximately hemispherical form shown in Figure 2. The rounded head 7 of a staybolt 8 will be inserted into the hollow hemispherical body and inward pressure will be applied to the fingers 9 formed by the notches 6 until the side edges of said fingers come together as shown at 6^a and the tool employed for this operation will be such that the portion of the device formed by the fingers 9 will be curved in conformance with the curvature of the other portion of the device, and the latter will have the form of a sphere except at the portion thereof having the opening 5^a for the passage of the bolt. The plug or member 5 has internal dimensions which are appreciably greater than those of the bolt head 7 and when the latter is mounted on the seat 10 around and in proximity to the opening 5^a, ample clearance space 11 will be afforded for the bolt head, and this is important in "flexible" staybolt structures.

The inner end portion of the staybolt is threaded as at 12 to screw through the inner boiler sheet, and said staybolt is provided at its inner extremity with an angular head 13 to receive a tool whereby the screwing of the bolt through the inner boiler sheet may be facilitated. After the staybolt shall have been installed, the head 13 will be removed and the inner end of the bolt will be upset as at 14. In order to assist in withstanding the end pressure on the bolt during the upsetting operation and to relieve the screw threads from excessive hammering pressure, a body of soluble material 15, such as salt, may be packed in the clearance space within the hollow plug.

It will be observed that the plug or member 5 forms a closure for the opening in the boiler sheet as well as a bearing member for

the bolt head, and by mounting said member so that it may be universally movable, it can be adjusted in a manner to insure accurate alignment of the staybolt with its 5 points of connection with the respective boiler sheets, whether said sheets be parallel or at an angle to each other, and when the combined bearing plug and closure shall have been properly adjusted, it will be firmly 10 united to the outer boiler sheet by means of a weld 16.

Instead of making the bearing plug and closure in a single piece, it may be made in a plurality of parts as shown in Figure 15 5 and secured together by a weld 17. The multiple-part plug may have a spherical shape as shown in Figure 5 or it may be tapering or conical as shown at 5^a Figure 8, to seat in a tapering, straight-walled opening 20 in the boiler sheet.

In the form of the invention shown in Figure 6, an elongated bearing plug and closure 5^b has a universally movable mounting at its inner end in the opening in the 25 boiler sheet, and at its outer end, it is provided with an angular head 18 to receive a holding tool. A weld 19 unites the plug 5^b to the outer sheet.

In the form of the invention shown in 30 Figure 7, an elongated tapering plug 5^c, is employed and mounted in a tapering opening in the boiler sheet, said opening having a straight wall as indicated at 20. This plug

is provided with an angular head 21 to receive a holding tool and it is united to the 35 boiler sheet by a weld 22.

Having fully described our invention what we claim as new and desire to secure by Letters Patent, is:

1. In a staybolt structure, the combination 40 with a boiler sheet having an opening, of a combined bearing member and closure having an initial universally movable mounting on the boiler sheet coincident with said opening and adapted to permanently 45 enclose the head of a staybolt, a staybolt having a head mounted in said member, and a weld securing said combined bearing member and closure to the boiler sheet.

2. In a staybolt structure, the combination 50 with a boiler sheet having an opening, of a spherical hollow plug having an opening and mounted in said opening in the boiler sheet, a staybolt having a head permanently 55 enclosed within said hollow plug and having a bearing therein, and a weld uniting said hollow plug to the boiler sheet.

In testimony whereof, we have signed this specification in the presence of two subscribing witnesses.

JOHN ROGERS FLANNERY.
ETHAN I. DODDS.
